UNITED STATES PATENT OFFICE.

JOHN W. ORSBURN, OF SPOKANE, WASHINGTON.

SACK-HOLDER.

1,133,395.

Specification of Letters Patent. Patented Mar. 30, 1915.

Application filed December 13, 1913. Serial No. 806,461.

To all whom it may concern:

Be it known that I, JOHN W. ORSBURN, a citizen of the United States, residing at Spokane, in the county of Spokane and 5 State of Washington, have invented new and useful Improvements in Sack-Holders, of which the following is a specification.

The object of this invention is to provide a gravity acting bag holder and releaser, 10 whereby a stack of bags may be held in convenient accessibility for use and readily withdrawn, one by one, from the stack while pressure is exerted upon the latter to hold the remaining bags.

15 A special object of the invention is to employ an open framework, whereby the margins of the bags disposed in stack form may be readily accessible at any elevation of the stack for withdrawal of single bags.

20 A further object is to provide a bag holder in the construction of which springs and all resilient parts may be entirely omitted and wherein the device is arranged and designed to function wholly by gravity.

25 Further objects and features of the invention will be more fully described in connection with the accompanying drawing, and will be more particularly pointed out in and by the appended claims:

30 In the drawing:—Figure 1 is a side elevation of a portion of a combined harvester, illustrating the application thereto of one form of the device of my invention. Fig. 2 is a plan view of the device of my invention 35 detached from the harvester. Fig. 3 is an end view thereof.

Like characters of reference designate similar parts throughout the different figures of the drawing.

40 It is well known that when empty bags are stacked on a harvester, the bags are frequently blown in the throat of the machine, the result being that the machine is not only clogged but the cylinder is often 45 broken. One of the special utilities of my invention is its use in connection with machines of this character, so that a stack of empty bags can be securely held in an accessible position for adjustment about the 50 discharge end of a loading stack, although it will be understood that my invention has a wide range of use apart from the particular utility illustrated.

As shown, 1 designates a combination having 55 a loading stack 2 for discharging the

grain adjacent to a platform or operator's stand 3.

The device of my invention, as shown, embraces an open framework, which may comprise a plurality, usually two, U-shaped bars 60 which perform the dual function of frame and guiding bars. The bases 4, of said bars are usually horizontally disposed, and the upright ends 5 thereof serve as side and guiding members of the frame, the horizontal portions 4 serving to support the stack. In the present form, the supporting and guiding portions of the frame are united by frame connecting portions 6, which are adapted to be anchored to a flooring by 70 screws or like devices for which holes 7 are provided. I desirably flatten the base or supporting members 4, as indicated at 8, so that the frame members can be connected by means such as rivets 9, in cases where the 75 frame members 4 are not directly anchored.

A stack of bags may be disposed upon the base members 4 and between the uprights 5, as illustrated in Fig. 1, and I will now 80 describe the novel means provided for holding the bags in stacked relation.

Gravity slidable members 10, preferably in the form of rods, are eyed at their ends, as indicated at 11, for slidable engagement with the upright frame members 5. Rollers, which may be in the form of lengths of pipe 12, are rotatably mounted on said rods 10 for direct engagement with the uppermost bag of the stack. The rollers 12 principally function as weights to normally 90 carry the rods 10 downwardly as the stacks decrease in height when bags are successively withdrawn therefrom. The rollers also facilitate withdrawal of the bags by reason of the fact that they will revolve 95 upon the non-rotatable and slidable bars 10 when the bags are withdrawn.

It will be seen from the foregoing that the device of my invention is entirely open throughout one area or side portion of the 100 bag stack 13, so that bags can be withdrawn therefrom, and readily grasped at different elevations of the stack, in other words, there is a free space for engagement of the uppermost bag by the hand of the 105 operator, and as the stack decreases in height, this free space will always be afforded down to the lowermost bag of the stack.

I have herein shown a form of the device 110 of my invention, which is especially adapted

for use in connection with stacks of grain holding bags where any plurality of gravity devices each comprising a non-rotatable and a rotatable member is provided, but I do not wish to be limited to this precise construction, and I further do not wish to be limited in any respects except for such limitations as the claims may import.

I claim:—

- 10 1. A releasable sack or bag holder comprising in combination, a supporting frame including upright rods engaging the sides of the stack of bags, a rod having eyes freely slidable onto and off from the ends of said rods and downwardly thereon, and a roller weight rotatably mounted on said eyed rod for engagement with the uppermost bag of the stack, substantially as described.
- 15 2. A bag or sack holder comprising in

combination, a plurality of U-shaped bars 20 adapted to extend beneath the bottom and upwardly along the sides of a stack of sacks or bags, a plurality of base bars connected with said U-shaped bars to form a rigid structure, rods having eye terminals freely 25 slidable onto and off from the ends of said U-shaped bars and downwardly thereon, and weight rollers rotatably mounted on said eyed rods for engagement with the top of the stack, substantially as described.

In testimony that I claim the foregoing as my own, I hereby affix my signature in the presence of two subscribing witnesses.

JOHN W. ORSBURN.
